UNITED STATES PATENT OFFICE.

JAMES M. RICHARDS, OF BRUNDIDGE, ALABAMA.

IMPROVEMENT IN COTTON-SCRAPERS.

Specification forming part of Letters Patent No. 222,367, dated December 9, 1879; application filed September 24, 1879.

To all whom it may concern:

Be it known that I, JAMES M. RICHARDS, of Brundidge, Pike county, State of Alabama, have invented Improvements in Cotton-Scrapers, of which the following is the specification.

A part of the specification is the accompanying drawings, in which Figure 1 is a perspective view of the plow; Fig. 2, a detached view of adjusting-block; and Fig. 3, a cross-section.

My invention relates to plows designed more particularly for scraping ridges of cotton or other small plants, but also adapted for use as ordinary plows; and it consists, first, in a construction whereby the scraper can be adjusted to different angles to suit the slope of the ridge; and, further, in the construction and also the combination of the several parts hereinafter more particularly specified.

A is the main beam of the plow, to which are connected the usual handles, and a standard, B, which is pivoted to a brace, H, which, together with the standard, is locked to the beam, the standard having a series of holes, *i*, through its upper portion, so that it may be lengthened or shortened, and when not bolted to the beam may be free to turn on its pivotal connection with the brace H, so as to be inclined to any angle desired.

A supplemental beam, D, shorter than the main beam, has a standard and brace constructed like that first described, and secured in like manner to said beam. This beam is connected to the main beam by means of two nutted bolts, E, passed through two clamp-plates, F F, one on the outside of each beam, conical washers being placed between the plates and the heads and nuts of said bolts, if desired.

The two beams are held apart from each other by means of a block, G, which is clamped between the beams by the bolts that hold them together. This block is of a form that will permit the supplemental or scraper beam to be thrown and held at any angle that will conform the scraper to the slope of the ridge, such a form being shown by Fig. 2, one end of the block being cut so as to describe a segment of a circle. The square end of this block is placed next to the main beam, and

the curved end next to the other beam, this last beam being set and held to any desired side angle by lengthening the lower bolt and shortening the upper one, or vice versa, as it is desired to increase or to lessen the angle of inclination of said beam, both Figs. 1 and 3 representing said beam at an inclination.

By setting the block G squarely between the two beams they are set in parallel lines with reference to each other; and by inclining the bottom of the block to the front or rear of the plow the short beam is made to diverge from the main beam at its front or rear, according as the block is set.

A hook, H', secured to the forward end of beam D hooks onto a stay, J, which braces both longitudinally and laterally the beam D, the said stay having one end bolted to the main beam, and the other end passed through said beam and the standard thereof, and held there by a nut on its end, so that it performs the twofold function of clamping the beam D and holding a standard to the main beam.

The cutting-blade to the main beam runs deeper than that to the supplemental beam, in order that the former may serve as a guide to hold the latter to its position.

When desirable, the supplemental beam may be detached and the main beam used for a single plow, or the two may be used together as a double stock, any form of blade being employed, and when so used the block G should be turned to present square ends, so that the beams may set perpendicularly; but when used as a cotton-scraper the block is so set while the beam D is at an inclination.

I claim—

1. The combination of beams A and D and intermediate block G, constructed to present bearings at different angles, and devices for clamping the block and beams together, substantially as described.

2. The combination of beams A and D, block G, and connecting-bolts, hook H, stay J, and standards B, substantially as set forth.

In testimony whereof I have signed my name to this specification in the presence of two subscribing witnesses.

JAMES M. RICHARDS.
